LLP

(57) **CLAIM**

The ornamental design for a vacuum cleaner attachment, as
shown and described.

DESCRIPTION

FIG. 1 is a front view of a vacuum cleaner attachment
according to my new design;

FIG. 2 is a rear view thereof;

FIG. 3 is a left side view thereof;

FIG. 4 is a right side view thereof;

FIG. 5 is a top plan view thereof; and

FIG. 6 is a bottom plan view thereof.

FIG. 7 is a perspective view thereof;

FIG. 8 is another perspective view thereof; and,

FIG. 9 is another perspective view thereof.

The portions of vacuum cleaner attachment shown in broken
lines form no part of the claimed design.

1 Claim, 9 Drawing Sheets
